UNITED STATES PATENT OFFICE.

WILLIAM LA HODNY, OF BUFFALO, NEW YORK, ASSIGNOR TO STANDARD MIRROR CO., INC., OF BUFFALO, NEW YORK, A CORPORATION OF NEW YORK.

DESIGN FOR A MIRROR BRACKET.

Application filed April 15, 1924. Serial No. 9,285. Term of patent 7 years.

To all whom it may concern:

Be it known that I, WILLIAM LA HODNY, a citizen of the United States, residing at Buffalo, in the county of Erie and State of New York, have invented a new, original, and ornamental Design for a Mirror Bracket, of which the following is a specification, reference being had to the accompanying drawing, forming part thereof, and in which—

I claim:

The ornamental design for a mirror bracket, as shown.

WILLIAM LA HODNY.
